UNITED STATES PATENT OFFICE.

THOMAS KIRBY AND ABRAM SINGER, OF PETOSKEY, MICHIGAN.

CAR-COUPING.

SPECIFICATION forming part of Letters Patent No. 373,987, dated November 29, 1887.

Application filed April 26, 1887. Serial No. 236,178. (No model.)

To all whom it may concern:

Be it known that we, THOMAS KIRBY and ABRAM SINGER, of Petoskey, in the county of Emmet and State of Michigan, have invented 5 new and useful Improvements in Car Couplers, of which the following is a full, clear, and exact description.

Our invention has for its object to provide an improved car-coupler so constructed and 10 arranged that it will be perfectly automatic and effective in action and can be conveniently used in connection with the ordinary draw-head and link-coupling.

The invention consists in certain novel features of construction and combinations of parts, 15 as hereinafter fully described, and then definitely claimed.

Reference is to be had to the accompanying drawings, forming a part of this specification, 20 in which similar letters of reference indicate corresponding parts in all the figures.

Figure 1 is a plan view, partly in section, showing the couplers in full lines about to couple and in dotted lines both coupled and uncoupled. Fig. 2 is a side elevation of our 25 improved coupling applied. Fig. 3 is a face view of the coupler. Fig. 4 is a sectional elevation of the same on the line $x-x$, Fig. 1. Fig. 5 is a detail view illustrating the pivoted coupling-block, its operating-lever, and spring.

A designates the draw-heads of the couplers, which are of like but reverse construction, and are formed on the usual draw-bars, B. Each draw-head A is formed in one side 35 with a longitudinal recess, C, opening laterally in a longitudinal slot, D. In the rear end of the recess C, on a vertical pin or bolt, E, is pivoted the enlarged inner end of the coupling-hook F, than which the recess C is some- 40 what deeper, but which is fitted to swing outward in the side slot, D. The recess C diverges forwardly to allow of a limited lateral play of the coupling-hook when in position for coupling, and a laterally-extending slot, 45 G, is cut in the rear part of the lower wall of the slot D, in which the hook F is rested when not to couple, as indicated in dotted lines in Fig. 1, the hook being raised to dis- 50 engage it from the outer wall of the recess C and swung rearward in the side slot, D, to said position of rest. The other side of the

draw-head A is formed with a rearwardly-extending recess, H, which is much deeper than the hook-holding recess C, and hence than the coupling-hook, in order to receive 55 hooks at different elevations. The upper and lower walls of the hook-receiving recess H extend horizontally to the rear, but the side walls, I, J, approach each other until the inner wall, I, is offset laterally to form a right-angled 60 shoulder, I', and the outer wall, J, is cut away to form a recess, J', in which the coupling-block K may swing.

The coupling-block K is adapted to swing laterally on a bolt or pivot, L, passed vertically through the draw-head at the rear outer part of the recess H and loosely through rounded lugs K' K² K³, projecting from the convex back of the coupling-block at the top, bottom, and a point therebetween, respectively. The face of the coupling-block K is straight vertically, but concave horizontally to correspond with the engaging-head of the coupling-hook F and to form a continuation of the converging side walls, I, J, of the recess 75 H when in position for coupling, so that the head of the coupling-hook will be accurately guided against the concave face of the coupling-block. Said concave face is arranged at one side of the pivot L, so that when the entering hook strikes the block the same will be 80 swung inward, the outer part of the concave face thereby forcing the head of the hook inward into engagement with the shoulder I', as indicated in dotted lines in Fig. 1.

Upon the vertical bolt or pivot L is also pivoted the operating-lever M, which rests on the medial lug, K³, and is pressed down thereupon by a spring, N, coiled on the pivot L between the lugs K' and K³. The inner end of the lever M terminates in a pronged extension, M', curved forwardly to engage the convex back of the coupling-block, and the outer handled end of the lever passes through a right-angled slot, O, in the side of the draw-head into a 95 position convenient for operating without the necessity of going between the cars. A straight shoulder, K⁴, is formed on the top of the medial lug, K³, and is adapted to engage the lever M at a point outwardly beyond the pivot L. 100 The lever M is held out of such engagement with the shoulder K⁴ when resting in the hori-

zontal branch of its guide-slot O, the block K being in position for coupling. When the coupling-block is swung on its pivot by the hook F, as before described, the outer arm of the lever M is swung forward in the slot O by the engagement of its extension M' with the back of the coupling-block, and is pressed downward by the spring N into engagement both with the shoulder O' at the forward end 10 of the slot O and with the shoulder K' on the coupling-block. The coupling-block is thus locked in its turned position, thereby securely holding the coupling-hook in engagement with the shoulder I'. In uncoupling, the lever M is raised from engagement with the shoulder O' and swung to the rear, thereby, through the action of its extension M', swinging the coupling-block outward and releasing the hook F.

A vertically-apertured keeper, P, is provided on the top of each draw-head A for use with the ordinary pin-and-link coupling. The rear wall, Q, of the recess H is curved to correspond with the curve of the rear inner part of the coupling-block K and its lugs K' K² K³, so that when the block is in its inner locking position it will have a broad bearing against the back of the recess H to withstand any shocks due to sudden stoppage, &c.

Having thus described our invention, what 30 we claim as new, and desire to secure by Letters Patent, is—

1. The combination, with one draw-head and its coupling-hook, of the other draw-head recessed to receive said hook and having a lateral shoulder to engage the hook, a coupling-block pivoted to swing in the draw-head toward and from said shoulder, and having a concave hook-receiving face arranged at one side of its pivot, a lever-arm swung by and 35 with the coupling-block, and a second shoulder on the draw-head to engage and lock the lever-arm, substantially as shown and described.

2. In a car-coupler, the draw-head formed 45 in one side with a hook-receiving recess and in the other side with a hook-holding recess, C, opening laterally in a slot, D, and a laterally-extending slot, G, in the lower wall of the slot D, the recess C being wider at its forward 50 end and deeper than the coupling-hook, and the slot D of equal depth therewith, in combination with the coupling-hook pivoted at the

rear end of the recess C, substantially as shown and described.

3. The draw-head formed with the recess H, 55 the upper and lower walls of which extend horizontally to the rear, the side walls, I J, of which converge, the wall I extending to a lateral shoulder or offset, I', the wall J to a lateral recess, J', in combination with the coupling-block K, having a vertically-straight concave face adapted to register with and form a continuation of the converging walls I J and to swing laterally toward the shoulder I', substantially as shown and described. 60

4. The draw-head formed with the recess H, the upper and lower walls of which extend horizontally to the rear, in combination with the coupling-block K, having a concave hook-receiving face, rearwardly-projecting curved 70 lugs, and pivoted at the rear outer part of the recess K, the rear wall, Q, of said recess being curved to correspond with the curve of the rear inner part of the coupling-block and its lugs, substantially as shown and described. 75

5. The draw-head formed with the recess H and coupling-shoulder I', in combination with the coupling-block K, adapted to swing toward and from the shoulder I', the pivot L, the operating lever M, swinging on said pivot and 80 adapted to engage the coupling-block on opposite sides of the pivot L, and the shouldered slot O in the draw-head, through which the lever extends, substantially as shown and described. 85

6. The combination, with the recessed draw-head, of the coupling-block adapted to swing laterally in said recess, having a convex back and formed with the upper, lower, and medial lugs, K' K² K³, the medial lug having a shoulder, K⁴, the pivot L, passed through the lugs K' K² K³, the lever M, having a curved extension, M', to engage the convex back of the block K, and the spring N, pressing the lever on the shouldered lug K⁴, substantially as 90 shown and described. 95
